United States Patent Office

Des. 190,761
Patented June 27, 1961

190,761

TABLE LIGHTER

John Beresford-Evans, Alton, England, assignor to Ronson Corporation, Woodbridge, N.J., a corporation of
New Jersey

Filed June 14, 1960, Ser. No. 60,999

Claims priority, application Great Britain Feb. 17, 1960

Term of patent 14 years

(Cl. D48—27)

FIG. 1 is a perspective view of a table lighter showing my new design;

FIG. 2 is an end elevation thereof;

FIG. 3 is an elevation thereof as seen from the opposite side of FIG. 2;

FIG. 4 is a top plan view thereof; and

FIG. 5 is a bottom plan view thereof.

I claim:

The ornamental design for a table lighter, as shown.
